[57] CLAIM

The ornamental design for a pocket for medical pants, as shown and described.

DESCRIPTION

FIG. 1 is a front and left perspective view of a pocket for medical pants showing my design in full lines with the broken line showing of environmental association matter being for illustrative purposes only and forming no part of the claimed design;

FIG. 2 is a top, front and right side view thereof;

FIG. 3 is a bottom, front and left side view thereof;

FIG. 4 is a front view thereof; and,

FIG. 5 is a back view thereof.
